UNITED STATES PATENT OFFICE.

NELSON GUYER, OF LIMA, OHIO.

LAMP-SUPPORTING ATTACHMENT.

SPECIFICATION forming part of Letters Patent No. 376,950, dated January 24, 1888.

Application filed July 13, 1887. Serial No. 244,192. (No model.)

To all whom it may concern:

Be it known that I, NELSON GUYER, of Lima, in the county of Allen and State of Ohio, have invented a new and Improved Lamp-Supporting Attachment, of which the following is a full, clear, and exact description.

This invention relates to a simple and exceedingly useful attachment for sewing-machines or tables, the object of the invention 10 being to provide for the supporting of a lamp above the table, and to provide for the storing and holding of the numerous articles that are used.

Reference is to be had to the accompanying 15 drawings, forming a part of this specification, in which similar figures of reference indicate corresponding parts in all the views.

Figure 1 is a side view of my attachment, parts 20 being broken away and shown in section, and the attachment being represented as it appears when connected to a sewing-machine table. Fig. 2 is an end view in partial section taken on line *x x* of Fig. 1, and Fig. 3 is an enlarged view representing the 25 connection between the attachment and the table, the table being shown in section. Fig. 4 is a cross-section on the line *y y* of Fig. 1.

In constructing such an attachment as the 30 one forming the subject-matter of this application I provide a supporting post or standard, 10, that is formed with a lower enlarged section, 11, and an upper enlarged section, 12, the lower end of the post or standard being threaded, as shown at 13, in order that it 35 may be engaged by a nut, 14, the threaded section of the post being passed through a proper aperture formed in the table in connection with which the attachment is to be employed. In the drawings this table is shown at 15 and 40 is represented as supporting a sewing-machine.

In applying the standard I provide an upper washer, 16, which is formed with a groove, 17, and I prefer to employ a lower washer, 18, 45 which acts as a wear-plate. Upon the post or standard 10 there is fitted a tube, 19, the enlargements 11 and 12 fitting closely within the tube. To the lower end of the tube I secure two downwardly-extending ribs, 20, 50 which are arranged to enter the groove 17

formed in the washer 16. To the upper end of the tube 19 I connect a cup-like receptacle, 21, that is adapted to receive and hold an oil-can, 22, and to one side of the tube I connect an outwardly-extending arm, 23, the upper 55 face of which is concave and open, the opening, however, being closed by a pin-cushion, 24, which is simply inserted in the opening; or the cushion might be hinged to one of the edges of the arm. This arm 23 supports a 60 lamp-socket, 25, and in order that the arm may be rigidly braced I provide a bracing-arm, 26, which is arranged as clearly shown in Fig. 1. This bracing-arm carries a number of upwardly-extending pins, 27, and downwardly-extending hooks 28, the pins 27 being employed for the purpose of holding the 65 spools, while the hooks 28 are useful in holding many of the small articles employed about the sewing-machine.

The lamp-socket is provided with an opening or slot, 30, through which the handle of the lamp passes, as indicated in Fig. 1.

In applying the washer 16 it is so adjusted 70 that the ribs 20 will be in engagement with the slot 17 when the attachment is in the position in which it is shown in Fig. 1, thus holding the lamp against accidental displacement in the most advantageous position in so far as the distribution of the light is concerned.

As before stated, the pins 27 are arranged 75 to carry spools, and when it is desired to reel the thread from said spools upon the bobbins used in the machine the frame is swung around to such a position that the thread may be drawn 80 from the spools to be reeled upon the bobbins as they are revolved upon the bobbin-carriers, the ribs at this time entering the recess 17 upon opposite sides of the standard.

Such an attachment as I have described 85 will be found to be exceedingly convenient and useful for the purposes for which it is intended.

Having thus fully described my invention, I 90 claim as new and desire to secure by Letters Patent—

1. In a lamp-supporting attachment, the combination, with a post or standard adapted for connection to a table, of a tube fitted upon said post or standard and having an arm sup- 95

the bottom, or otherwise, one, two, or more lines or spaces C, out of line with the numerals 1, 2, 3, 4 in the first transverse space D, are corresponding numerals 1, 2, 3, 4, forming a 5 second index, E. Other characters in place of the numerals 1, 2, 3, 4—such as letters of the alphabet—may be used in the two indexes at opposite ends of the check, and such would be the equivalent of numerals.

10 In filling out the check the sum for which the said check is drawn is written out in words on the line or space C in which occurs the name of the highest denomination in the sum of the check—as, for instance, if the highest denomination 15 in the sum is thousands, the words should be written upon the thousands space or line C. If the highest denomination mentioned is hundreds, the words should be written upon the line or space C marked “hundreds,” and so on if the highest denomination 20 be tens or units, or whatever it may be. Furthermore, the sum of the check should be commenced to be written directly under the numeral over the upper line or space C in the 25 numbered columns or spaces D representing the number of the highest denomination mentioned in the sum. These directions may be more briefly expressed by stating that the sum of the check should be commenced to be written 30 directly under the figure expressing the sum of the highest denomination to be written, and on the line of the same denominational name. For example, if the highest denomination 35 and amount is two thousand, the writing of the sum should begin under the numeral 2 over the upper line or space C, and should be upon the line or space C marked “thousands,” as shown in Fig. 2. In case there is not room for the whole sum to be written in the line or 40 space C in which the writing is begun, it can be completed in the next space.

This so far does not essentially differ from the safety-check described in my Letters Patent hereinbefore referred to. By combining, 45 however, with this arrangement of numerals, words, and lines and spaces the second index, E, having its numerals which correspond to the numerals in the index on the opposite end of the check out of line with them by one, two, 50 or more spaces C, I very materially improve the safety character of the check, without having to resort to puncturing it or inserting by the pen special numbers on different lines or spaces indicating the amount. Thus the 55 nature to the check is commenced upon a line or space C below that on which the amount was commenced to be written, (here shown in Fig. 2 as the second space or line C below;) but the number of lines below, it will be obvious, may be changed. The signature is 60

commenced to be written upon such lower line or space C directly under the first word of the sum written, such line or space being the one upon which the numeral in the index E is that corresponds with the numeral in the 65 opposite or left-hand index upon the space or line C above on which the sum was commenced to be written. For example, in Fig. 2 the signature is commenced to be written under the first word “two” of the amount on the 70 space or line C numbered 4 in the left-hand index, and is written commencing in the space D numbered 2 (which expresses the sum of the highest denomination in the amount) 75 upon the second line or space C below, which is numbered 4 in the index E, corresponding with the number in the other index upon which the amount was commenced to be written, and which number indicates the highest denomination of the amount.

The same method holds good whatever the highest denomination or sum of the highest denomination may be, and whether the amount be made up of several denominations or one only, the lines and spaces in which the amount 85 and signature are commenced to be written of course being changed to suit. This makes a duplex check, which will readily indicate upon the face of it, both in viewing the amount and the signature, or either, whether the check 90 is genuine or has been altered. Furthermore, the sum of the largest denomination written on it cannot be changed without rewriting the signature to correspond, which would make a new check, and consequently release the maker 95 of the original check from all responsibility.

Having thus fully described my invention, I claim as new and desire to secure by Letters Patent—

A blank draft, check, money order or instrument made, substantially as herein shown and described, with a series of longitudinal spaces or lines, C, and cross-spaces D, a series of consecutive numbers or characters and denominational names applied to said spaces or 100 lines C at or near one end of the check or instrument, an additional index, E, composed of a series of corresponding numbers or characters applied to the spaces or lines C at or near 105 the opposite end of the instrument out of line with the numerals or characters on said spaces or lines at the other end of the instrument, and a series of consecutive numbers applied to the cross-spaces D, or certain of them, as and for the purposes set forth.
